Application February 10, 1934, Serial No. 710,629
In Germany February 28, 1933

12 Claims. (Cl. 62—118)

My invention relates to refrigeration and more particularly to the production of refrigeration involving intermittent operating apparatus and has for its principal object to efficiently utilize a 5 source of periodic low temperature.

A more specific object of my invention is to increase the efficiency of absorption refrigerating apparatus of the intermittent type applied to the production of refrigerating temperatures of not 10 extremely low value. Another object is to produce substantially continuous refrigeration from an intermittent cooling source without resorting to a plurality of machines or devices of like type or a plurality of heat sources.

15 In accordance with a preferred embodiment of the invention, a discontinuous source of cold, particularly of low temperature, is utilized to produce substantially continuous refrigeration, advantageously by means of a plurality of vaporization-condensation members. A low temperature source condenses refrigerant and causes withdrawal thereof from an absorbent and the heat for expelling the refrigerant from the absorbent is withdrawn from the body to be cooled. This 20 heat is withdrawn at higher temperature than that of the low temperature cooling source and can cause a cooling of the body to be cooled, so that, by also withdrawing heat from the body to be cooled by evaporation of the condensed refrigerant, I can obtain cooling both while refrigerant is condensed and while it is absorbed.

Furthermore, since the heat of condensation (latent heat of vaporization) is withdrawn during the condensation period, together with the 25 heat of absorption, and since the heat of condensation is also withdrawn during the absorption period, and since the heat of condensation at the higher temperature of withdrawal from the body to be cooled is substantially the same as at the lower temperature of the intermittent low 30 temperature cooling source, I obtain twice the take-up of heat (production of cold) that is represented by the action of the low temperature cooler. Thus my invention is capable of doubling 35 the efficiency of an intermittent cooling source or system.

The nature and advantages of my invention will be apparent from the following description considered in connection with the accompanying 40 drawings forming a part of this specification, and of which:

Fig. 1 is a more or less diagrammatic view of 45 an apparatus embodying the invention, including an intermittent absorption system for producing the low temperature cooling source; and

Figs. 2 and 3 show other embodiments of the invention.

Referring to Fig. 1, 10 designates the evaporator of an intermittent absorption refrigeration system which may be, for example, of the kind disclosed in my copending application, Serial No. 701,123, filed Dec. 6, 1933. The evaporator 10 is an intermittent source of cold of low temperature and is but one such source usable with the present invention. Other examples of cooling source are 10 the evaporator of a compression type refrigerating system and solidified carbon dioxide (dry-ice).

In order to better understand the invention, I will first describe the intermittent system including evaporator 10, though this system enters into 15 the present invention only to give an example of a low temperature source and a system which can be made more efficient by the present invention.

The initial system includes an absorption liquid reservoir 11 exposed to the cooling effect of atmospheric air. This reservoir is filled with a solution of refrigerant in absorbent, which may be ammonia dissolved in water as absorption liquid. To one side of the reservoir 11 is a generator 12 which may be heated by any suitable source, as 20 a gas flame or an electric heater. Assume that the flue 13 extending through the generator is suitably heated during refrigerant expulsion periods. Conduits 14, 15 and 16 connect the lower part of generator 12 with the lower part of vessel 30 11. A conduit 17 connects the upper part of vessel 11 with a thermo-syphon coil 18 disposed to receive heat as by being wound around flue 13 in contact therewith. The upper part of coil 18 is connected to the upper part of the generator 35 by means of a conduit 19. The upper part of the generator is connected by means of a conduit 20 with the upper part of vessel 21, the lower part of which is, in turn, connected by a trap conduit 22 with a lower vessel 23. A conduit 24 40 connects the upper part of vessel 23 with the top part of a condenser 25 which may be exposed to the cooling influence of surrounding air. The condenser as well as the absorber-reservoir may be provided with cooling fins as indicated on 45 the drawings. Water cooling may be used instead of air cooling. The lower part of the condenser 25 is connected by means of vertical pipe 26 with the upper part of a second condenser 27 which is situated above evaporator 10 and which 50 is connected to a dome 28 of the evaporator 10.

Extending upwardly within vessel 23 is a conduit 29 which is connected to a conduit 30. Conduit 30 connects conduit 15 with the upper part 55 of a volume variation vessel 31. Conduits 15 and

17 pass in heat exchange relation as shown at 32. A conduit 33 extends between reservoir 11 and volume variation vessel 31. A conduit 34 connects the upper part of the volume variation vessel 31 with the conduit 20. A drain conduit 35 is connected at the top to condenser 27 and at the bottom to the absorber-reservoir 11 or other part of the absorption liquid part of the system. Connected to conduit 35 is a U-tube 36 which opens within a conduit 37 closed at the top and communicating at the bottom with a low liquid containing part or header 38 of the evaporator 10. The upper part of the evaporator which may be designated as 39 is connected to the lower header 38 by means of two vertical pipes 40 and 41.

Suitable controlling mechanism may be provided to control the operation of this initial or primary system. The control of such a system is described in my aforesaid application Serial No. 701,123, and inasmuch as the system in general is there described and inasmuch as the present invention does not depend on what kind of a system is used for the obtaining of the intermittent low temperature cooling source, I will merely briefly describe the process of operation and if a more detailed consideration is desirable, reference may be had to my aforesaid copending application. The system operates with alternate periods of absorption and expulsion. During the expulsion period heat is supplied to the generator 12 and the thermo-syphon coil 18. By this means a circulation is set up between generator 12 and the reservoir 11. Strong absorption liquid flows from vessel 11 through conduit 17 and into the thermo-syphon coil 18, where refrigerant vapor is expelled from solution and produces a lifting effect on the liquid. The vapor and liquid passes upwardly into the generator 12. It will be understood that the coil 18 is a part of the generator or the member 12 may be considered as a separating vessel and may even be unheated if sufficient heat is applied to coil 18. In the generator 12 further vapor is driven from solution due to heating the same and the weak solution flows downwardly therein and passes through conduits 14, 15 and 16 to the vessel 11. The vessel 11 is filled with liquid and the weak liquid is admitted at the bottom and the strong liquid withdrawn from the top so that there is a progressive rise of quantity of weak liquid upwardly in vessel 11.

Vapor expelled in the coil 18 and vessel 12 passes through conduit 20, through conduits 22 and 24 and into condenser 25 where most of it is liquefied. Liquid is contained within the vessel 31 and this vessel may be insulated or somewhat heated and provides a stagnant layer of liquid over the main body of absorption liquid so that a pool of concentrated solution is formed in communication with the generator through conduit 34 during the expulsion periods which prevents substantial absorption of refrigerant vapor. No flow takes place through conduit 30 at this time. The liquid condensed in condenser 25 with some gas is forced, due to the pressure in the hot part of the system, through pipe 26 into the condenser 27 where any remaining vapor is condensed and the liquid falls down into the evaporator 10 and accumulates there. When the evaporator has filled up to a certain level, which level should be within the dome 28, liquid overflows through the drain bend 36 and into the liquid portion of the system. The

drain arrangement 36-37 automatically takes out absorption liquid from the evaporator and the system may be controlled by the overflow of pure ammonia as described in my aforesaid copending application. Some impulse is utilized to 5 shut off the heat and thereupon the generator cools. Cooling of the generator causes liquid to be drawn up into the seal or trap conduit 22. The rate of absorption due to this cooling may be enhanced by separate pools of absorption liquid or by other means. The lower pressure in the generator relative to the evaporator causes liquid to be lowered in tube 29 until gas can enter tube 30 through conduit 29. This sets up a circulation of liquid upwardly in conduit 30 15 due to the entrance of gas thereinto from the conduit 29 and consequently from the evaporator, downwardly through vessels 31 and 11 and through conduits 16 and 15 back to conduit 30. The absorption period is now under way and the refrigerant in evaporator 10 is evaporated and takes up heat, thus producing cold. The absorption period continues until some impulse changes the regulation so that the heating is again started. This may, for instance, be a rise 25 of temperature of evaporator 10.

An intermittent system of this type can be operated to give very low evaporator temperature, for example, -20° F. During the heating period, the temperature of evaporator 10, at least 30 the upper part thereof, will rise to the temperature of condensation in condenser 27. Thus we have a source of cold which intermittently operates between for example 90° F. and -20° F., and the present invention aims to solve the problem of obtaining continuous refrigeration from 35 this source at an intermediate temperature and with greater efficiency than the efficiency of the apparatus which varies the temperature of the evaporator 10.

Coming now to the present invention, a conduit 100 extends through the header 38 of the evaporator 10. This conduit is connected at its bottom end to the upper part of an evaporator 101 situated within or in heat exchange relation with 45 a space 102 to be cooled. This space will be referred to as the body to be cooled, but it will be understood that the invention is not limited to any particular body to be cooled whether it be stagnant air or flowing air or a solid body. The 50 body to be cooled is surrounded with insulation 103 which also surrounds the greater part of the evaporator 10 and certain other apparatus presently to be described. The upper part of conduit 100 is connected to a vessel 104 which I 55 will term a generator or generator-absorber. This vessel contains a solid absorbent 105 suitably disposed in a retaining structure as is known in the art. The solid absorbent may be prepared calcium chloride or other dry absorbent as is 60 known. Generator 104 and evaporator 101 and conduit 100 form an intermittent absorption system which is separate from and in heat exchange relation with the intermittent system previously 65 described. The conduit 100 is the condenser of the system 101-100-104. This system I will designate as system A and the previously described or initial system I will designate as system B. It will be seen that the condenser of 70 system A is in heat exchange relation with the evaporator of system B. The generator 104 of system A is also imbedded in the insulation 103. The systems A and B are each hermetically sealed and are non-communicating.

A vaporization-condensation member 106 which is hermetically sealed and which is partially filled with a volatile liquid such as, for example, ammonia, propane, or methyl chloride, has its vapor space 107 in heat exchange relation with the generator 104, and its liquid space 108 in heat exchange relation with the body to be cooled. Another vaporization-condensation member 109, likewise hermetically sealed and partially filled 10 with a volatile liquid such as that in member 106, has its liquid space 110 in heat exchange relation with generator 104 and its vapor space 111 exposed to the cooling of the atmosphere or other cooling source. The liquid level in the member 109 should be within the insulation as disclosed.

The combined operation of systems A and B or what may be termed the entire system is as follows:

20 Assume that liquid refrigerant, for example, ammonia, has been filled into the evaporator 101 to the level K. Assume that there is relatively little refrigerant absorbed in the solid absorbent in generator 104. Assume that a heating period 25 is starting in system B and that there is liquid in evaporator 10 to the low level M. As heating continues in system B refrigerant is driven from solution and condenses in condensers 25 and 27 and flows into evaporator 10. Although this 30 heats up the evaporator 10, it has but small effect on system A since the liquid in header 38 is stagnant. In the meanwhile the solid absorbent in the generator 104, which is now acting as an absorber, absorbs refrigerant and lowers the pressure, wherefore the pressure is reduced by communication through pipe 100 on the level of pure liquid refrigerant in evaporator 101. This reduction of pressure in evaporator 101 causes evaporation. This evaporation results in withdrawal 40 of heat from the body to be cooled 102. The heat of condensation and absorption given off in the generator-absorber 104 heats the liquid in the space 110 of the upper vaporization-condensation member 109 and this liquid boils or 45 evaporates and the vapor passes upwardly into the condenser 111 of member 109. The atmosphere cools the condenser 111 and the condensate flows back down into the liquid space 110 to be again vaporized. It will be seen that, during this 50 time while the evaporator 10 is filling with condensate, system A is operating like an ordinary simple intermittent absorption apparatus and producing refrigeration by vaporizing refrigerant in the evaporator and rejecting heat of absorption 55 from the generator-absorber to a natural cooling source such as the atmosphere. This continues until evaporator 10 is filled with liquid or possibly not so soon if all the liquid refrigerant or substantially all is vaporized out of the evaporator 101, in which case this evaporator becomes 60 ineffective for the remainder of this period while the evaporator 10 is filling up to the overflow point as at level P or to such level as is determined by the control when the heating period of system B is stopped. Some controlling impulse 65 will sooner or later terminate the accumulation of liquid refrigerant in evaporator 10 and stop the heating of coil 18 and generator 12 of system B.

70 Now the absorption period of system B will begin. The pressure is quickly lowered in this system for reasons previously explained and as outlined more in detail in my copending application above referred to, and the evaporator 10 will very 75 soon pull down to a low temperature which may

be as low as -10° or -20° F. or even lower. The temperature of the evaporator 10 is reduced due to the vaporization of the liquid refrigerant and heat is drawn up into this liquid. Inasmuch as there will be ebullition throughout the liquid space 5 of the evaporator 10, this cold temperature will be immediately communicated down to the conduit 100 and thus the system A is provided with a condenser operating at, for example, -20° F.

This cold applied to system A will cause condensation of refrigerant therein. The ammonia or other refrigerant in the system will condense in the conduit 100 and flow down into the evaporator. This will not heat the body to be cooled because of the low temperature prevailing. It 15 will instead produce some cooling of the body to be cooled by the inflow of the very cold condensed refrigerant into evaporator 101 and vaporization therein due to the condensation. In this connection, it is preferable to partially or wholly insulate the evaporator 101 so that it can pull down to the same temperature as condenser 100 so that it cannot act as a substantial source of vapor for condenser 100. Evaporator 101 is well suited to be insulated and constitute an ice freezing chamber for a refrigerator cabinet. The cold temperature produced in the condenser 100 and the evaporator 101 causes a decrease of pressure which, considering the relatively high temperature of the generator 104, causes refrigerant to be 20 expelled from the absorbent therein, and thus we are now on a heating period of the system A. However, this heating period differs from the ordinary intermittent apparatus in that the heat supplied for the expulsion of the refrigerant from 25 the absorbent is withdrawn from the body to be cooled through the member 106. This is possible due to the fact that the condenser 100 is at so low a temperature. Suppose, for example, that the condenser 100 has a temperature of -20° F. 30 The generator 104 can then operate at a temperature of, for example, 32° F. It can expel the refrigerant at this temperature and consequently any higher temperature body can supply the necessary heat to take care of the heat of vaporization and the heat of absorption. Inasmuch as 35 the body to be cooled is at, for example, 40° F., which is even a low temperature for the food space of an ordinary refrigerator, the body to be cooled can supply the heat necessary for the operation of the generator 104 in expelling the refrigerant from absorbent.

The temperature of the generator 104 is at this time lower than the temperature of the condenser 111 and therefore there will be no heat 55 transfer through the member 109 and the liquid therein will be stagnant. This period which is the expulsion period of system A and the absorption period of system B will continue substantially until the control of system B turns on 60 the heat again. Also in this case the effective take-up of heat in the system A may not be coincident with the time of the evaporation in system B, this of course depending upon the design of the apparatus. The system A should 65 be so dimensioned that its periods are substantially coextensive with the periods of system B. This is generally merely a question of making the generator 104 large enough with reference to the volumetric content of evaporator 10. 70

As above indicated, the evaporator 101 should preferably not take up heat during the expulsion period of system A in order that the condensation will draw refrigerant from the generator 104; whereas it should take up heat dur- 75

- ing the absorption period of system A so that the refrigerant can return to the absorbent. If desired, this action can be carried out mechanically by placing evaporator 101 in an insulated 5 passage or flue having one or more openings for air circulation controlled by a damper or vanes automatically opened and shut due to temperature in evaporator 10; low temperature shutting off air flow and isolating evaporator 102, and 10 high temperature opening the passage to allow air flow to supply heat to evaporator 101.

Thus it will be understood that, during the heating period of system B, refrigeration is produced in the body to be cooled 102 by evaporation 15 of refrigerant in evaporator 101. During this period, an amount of refrigeration is taken up substantially corresponding to the heat of condensation of the refrigerant in evaporator 101. By heat of condensation I mean what is 20 otherwise termed latent heat of vaporization. During the absorption period of system B, the refrigerant is driven off from the generator-absorber 105 and takes up heat from the body to be cooled which heat is also substantially equal 25 to the heat of condensation (latent heat of vaporization) of the refrigerant to which is added the heat necessary for expelling from absorbent in addition to the heat of condensation which is usually known as the solution heat. Thus, while 30 the refrigerant in system B has one cycle including one withdrawal of heat of condensation, the refrigerant in system A takes up the heat of condensation twice, and a little more, from the body to be cooled. The heat of condensation is 35 substantially the same at the higher temperature of operation of generator 104 as the heat of condensation of refrigerant at the lower temperature in evaporator 10 during the absorption period. Thus, by taking out the heat at the 40 higher temperature, I am able to obtain substantially twice the refrigerating effect that is produced by the system B per se.

The temperature produced in the body to be cooled 102 can be automatically regulated by 45 applying a regulating valve or switch or the like controlling the supply of heat to generator 12 responsive to temperature of the body to be cooled, and operating to decrease the supply of heat on drop in temperature. This will delay the starting 50 or lengthen the time of the heating period of system B.

Fig. 2 shows another embodiment of the invention. Like reference characters designate corresponding parts. Within the evaporator 10 is a 55 condenser coil 100a forming a part of the system A. The condenser 100a opens in the bottom of a receiver 115 which is in heat exchange relation with and built around the lower part of evaporator 10. The upper end of condenser conduit 100a communicates with an evaporator vessel 101a. Evaporator vessel 101a communicates through conduit 100b with a generator 104 containing solid absorbent. The member 60 109 is essentially the same as the correspondingly marked member in Fig. 1 and includes a liquid space 110 and a condensing space 111, the liquid space being within or in heat exchange relation with generator 104 and the condenser space 111 being exposed to the atmosphere or 65 other natural source of cooling. The member 106 has a gas space 107 within or in heat exchange relation with generator 104 and the lower part is arranged so that it has a gas space 116 built around and in heat exchange relation with evaporator 101a. This system has a single ultimate 70

evaporator 117 which may include tubes or sheet metal structure connected to the member forming space 116 so that the level of liquid is preferably as shown, though it may be higher or lower. The evaporator 117 may be of any form depending upon the substance to be cooled. For example, for conditioning flowing air it may be merely a flanged pipe or series of pipes. 5

In the operation of this system, assume that system B is operating with an absorption period. 10 The condenser 100a is cooled to a low temperature and causes condensation of refrigerant in system A. This condensation results in accumulation of liquid refrigerant within receiver 115 and a reduction in pressure in system A so that refrigerant is expelled from absorbent in generator 104. The generator acts as a condensing medium for the member 106 as in the previous case and condensation takes place in space 107 resulting in evaporation of liquid refrigerant in member 117. 15 Thus heat is withdrawn from the body to be cooled during the period which is the absorption period for system B and which is the generation period for system A. 20

At the end of this period, the evaporator 10 25 has been substantially deprived of liquid content, and liquid ammonia is supplied thereto. The heat applied to evaporator 10 causes a rise of pressure in receiver 115 due to rise of temperature and gas is evolved in receiver 115 which forces 30 or presses the liquid from receiver 115 through tube 100a and into evaporator 101a so that the latter becomes filled to, for example, the level K. The liquid is forced out of vessel 115 from, for example, the level Q to the level R. When 35 this liquid has been pressed out of receiver 115 and into evaporator 101a the heat contained in evaporator 10 has substantially no effect on the refrigerant since vessels 10 and 101a are separate and spaced within insulation 103. The small 40 amount of heat conducted through conduit 100a is insignificant. The temperature of evaporator 101a can now rise or is already at a relatively high value wherefore evaporation takes place in this vessel and the evaporated refrigerant is absorbed in the absorbent 105 in generator 104. Evaporator 101a now acts as a condensing medium for the evaporator 117 due to the cold produced by the evaporation and liquid is boiled off or 45 evaporated in member 117 and passes upwardly 50 and is condensed on the outside of vessel 101a and the condensate falls downwardly within space 116 and back into evaporator 117 to be re-evaporated. For this period which is the absorption period of system A the heat of absorption 55 (including the heat of condensation) is given off by means of the vaporization-condensation member 109 as explained in connection with the previous embodiment.

The difference between Fig. 2 and Fig. 1 may be 60 briefly summarized by stating that the condenser of system A in Fig. 2 is isolated from the evaporator of system A so that during the absorption period of system B the condensation in the condenser of system A cannot act as a heat withdrawing means for the body to be cooled which is connected to two condensing spaces one of which is in heat exchange relation with the generator-absorber of system A and the other of which is in heat exchange relation with the 65 evaporator of system A.

The apparatus shown in Fig. 3 is similar to the apparatus shown in Fig. 2 but differs in the following respects: The evaporator 117 is altered to one serving merely to cool at high tempera- 70 75

ture. For low temperature cooling a separate evaporator 120 is provided which may be made as a sheet metal box structure having an upper header 121 and a lower header 122 and provided with shelves through which the refrigerant may circulate and which are adapted to hold ice trays. Evaporator 120 is imbedded in the insulation 103 and is provided with a suitable door opening. The upper header 121 is connected by means of a conduit 123 with the lower part of evaporator 10. The drain arrangement 36-37 is connected to the lower header 122. The evaporator 117a operates in the manner described in connection with Fig. 2. The evaporator 120 is intermittently cooled to the low temperature of evaporator 10 and therefore is suitable for the production of ice, which does not involve continuous heat supply in large quantity. During the heating period of system B, evaporator 120 is not substantially heated because of the stagnant condition of the liquid contained therein.

It will be understood that the invention is not limited to an intermittent absorption apparatus as the low temperature cooling source but that the low temperature cooling source may be of many varieties as for example, solidified carbon dioxide inserted periodically in a container in heat exchange relation with the condenser 100 of Fig. 1; or a compression refrigerating machine may provide the low temperature source by starting and stopping the same at suitable time intervals. It is also not necessary that a dry absorbent be used although I prefer this in order that the apparatus shall be more effective and simple in construction. If a liquid absorbent is used in system A it is necessary to provide some means for draining absorption liquid from the evaporator to the generator as is necessary or advantageous with system B. Such drainage devices are known per se and need not be further outlined.

Instead of ammonia and water in system B, a different refrigerant, as, for example, methyl-amine, may be used and a different solvent, as, for example, ethylene glycol, may be used.

It will be understood that the generator-absorber 104 may be situated independently of the other parts.

In the system shown in Fig. 2, the entire system E and condenser 100a may constitute a self-contained unit and be situated at a low level whereas the rest of system A may be at a much higher level. Also two separate ultimate evaporators may be used in Fig. 2 in different cabinets remote from system B.

It will be clear that a great variety of departures may be made from the disclosure without departing from the spirit or scope of the invention.

I claim:

1. A converter for transforming periodic refrigeration into substantially continuous refrigeration comprising an intermittent absorption system including a condenser adapted to be subjected to the periodic refrigeration, an evaporator and a generator-absorber, and single unidirectional means to conduct heat to both said evaporator and said generator-absorber from a body to be cooled.

2. A refrigeration system including an evaporator, a generator-absorber connected to said evaporator, a condenser connected to said evaporator, means for intermittently cooling said condenser, and single unidirectional heat transfer means for conducting heat from the body

to be cooled to both the evaporator and the generator-absorber.

3. A refrigeration system including an evaporator, a generator-absorber connected to said evaporator, a condenser, means to intermittently cool said condenser, single means employing vaporization and condensation of a fluid for conducting heat from the body to be cooled to both the evaporator and the generator-absorber, and means employing vaporization and condensation of a fluid for conducting heat from the generator-absorber to a cooling source.

4. Refrigeration apparatus including an evaporator in heat exchange relation with a body to be cooled, an intermittent absorption system including an evaporator, a condenser, and a generator-absorber, means for intermittently cooling said condenser, a second condenser for fluid in the first-mentioned evaporator in heat exchange relation with said generator-absorber, and a third condenser for fluid in the first-mentioned evaporator in heat exchange relation with the second mentioned evaporator.

5. Refrigeration apparatus comprising a first evaporator, a second evaporator, a third evaporator, a condenser in heat exchange relation with said first evaporator and communicating with said second evaporator, a second condenser in heat exchange relation with said second evaporator and communicating with said third evaporator, a generator-absorber communicating with said second evaporator, and a third condenser in heat exchange relation with said generator-absorber and also communicating with said third evaporator for withdrawing heat from a body to be cooled.

6. Refrigeration apparatus comprising a first evaporator, a second evaporator, a third evaporator, a condenser in heat exchange relation with said first evaporator and communicating with said second evaporator, a condenser in heat exchange relation with said second evaporator and communicating with said third evaporator, a generator-absorber communicating with said second evaporator, and a condenser communicating with said third evaporator and in heat exchange relation with said generator-absorber.

7. A method of refrigeration which includes alternately expelling and absorbing refrigerant fluid vapor with respect to an absorbent therefor, condensing the expelled refrigerant to liquid at a temperature below that at which said expulsion takes place, withdrawing heat in a single thermal path from a body to be cooled, and transferring the withdrawn heat to said refrigerant to cause said expulsion thereof from the absorbent and alternately to cause evaporation thereof.

8. A method of refrigeration which includes removing heat from a body to be cooled by vaporization of liquid, and causing condensation of the resulting vapor by intermittent heat transfer to cause expulsion of refrigerant vapor from an absorbent and alternate heat transfer to cause evaporation of refrigerant liquid, and forming said refrigerant liquid by intermittent condensation of said expelled refrigerant vapor.

9. In a refrigerator having a thermally insulated compartment, refrigeration apparatus including an intermittent cooling element, an evaporator, a generator-absorber connected to said evaporator, a condenser in thermal transfer relation with said cooling element and connected to said evaporator, a second condenser

- having a portion in thermal exchange relation with said evaporator and another portion in thermal exchange relation with said generator-absorber, and a second evaporator in said insulated compartment and connected to said second condenser, said first condenser being constructed and arranged to intermittently receive vapor from and alternately deliver liquid to said first evaporator responsive respectively to decrease and increase in temperature of said intermittent cooling element, and all of said refrigeration apparatus parts being thermally insulated against loss or interchange of heat except as stated.
- 15 10. In combination with an intermittent cooling element, a converter for producing substantially continuous refrigeration comprising an intermittent absorption refrigeration system including a generator-absorber and an evaporator, means to conduct heat from a body to be cooled to both said evaporator and said generator-absorber, and a condenser in said system and in thermal exchange relation with said intermittent cooling element, said condenser being constructed and arranged to intermittently receive vapor from said generator-absorber and alternately deliver liquid to said evaporator by vapor lift action responsive respectively to decrease and increase in temperature of said intermittent element.
- 20 25

11. Refrigeration apparatus including a vaporization-condensation member having a plurality of condensation portions, an intermittent absorption refrigeration system having a generator-absorber in thermal exchange relation with one of said portions and an evaporator in thermal exchange relation with another of said portions, an intermittent low temperature cooling element, and a condenser in said intermittent system arranged to be intermittently cooled by said element. 5

12. In a refrigerator, an absorption refrigeration system having alternate generating and absorption periods and including an evaporator, a condenser, and a generator and absorber, an auxiliary system including a second generator-absorber, a second condenser, and a second evaporator, said second condenser being arranged to be cooled by said first evaporator during the absorption period of said absorption refrigeration system, means to cool said second generator-absorber only during the generating period of said absorption refrigeration system, and means to conduct heat to both said second evaporator and said second generator-absorber whereby 25 cooling of said refrigerator occurs continuously during both generating and absorption periods of said absorption refrigeration system. 20

CARL GEORG MUNTERS. 30
